UNITED STATES PATENT OFFICE.

THOMAS L. CAMPBELL, OF BERLIN, PENNSYLVANIA.

MINE-CAR SKID.

Application filed August 4, 1920. Serial No. 401,159.

To all whom it may concern:

Be it known that I, THOMAS L. CAMPBELL, a citizen of the United States, residing at Berlin, in the county of Somerset and State 5 of Pennsylvania, have invented certain new and useful Improvements in Mine-Car Skids; and I do hereby declare the following to be a full, clear, and exact description of the invention, such as will enable others 10 skilled in the art to which it appertains to make and use the same.

This invention relates to a mine car skid for use in connection with cars used in coal and other mines and used as a brake for re- 15 trading movement of the cars and preventing the cars from traveling rapidly down an incline. Cars such as are used for carrying coal from a mine are not provided with brakes and therefore the improved skid has 20 been provided for use upon the tracks, the skids being connected with the forward end portion of the car and the wheels of the car moving on to the skids so that they will be raised out of engagement with the track 25 and the car thus caused to slide instead of moving freely along the track.

Another object of the invention is to so construct the improved skid that it may be readily put in place and connected with the 30 forward end portion of the car and to further so construct it that it will be very strong and durable and not liable to break.

This invention is illustrated in the accompanying drawing wherein,

35 Figure 1 is a side elevation showing a car upon a track with the improved skid in place.

Figure 2 is an enlarged perspective view of the skid.

40 Figure 3 is a transverse sectional view through the skid showing the same in place upon a rail.

Figure 4 is a detail side elevation of the attaching hook employed.

45 This improved skid 10 is formed from a strip of angle iron which is provided with a depending side flange 11 for engaging the inner side of the head of the rail 12 as shown in Figure 3 so that the flange of a car wheel 50 may engage this depending side flange 11 and hold the skid in tight engagement with the rail and thus prevent danger of the skid being moved outwardly and caused to drop off of the rail when in use. This flange

11 is cut away from the forward and rear 55 end portions of the skid and the skid is provided with a longitudinally extending depression thus providing side ribs 13 as shown in Figure 3 between which the skid is provided with openings 14. These openings 14 60 are used as sand retainers, that is, to catch sand which is dropped at intervals by the mine locomotive, to distribute the sand over the track to thereby afford greater resistance to the skid especially on grades. 65 The forward end portion of the skid is bent upwardly to provide a tongue 15 which tongue is provided with openings to receive fastener bolts 16 which pass through the inner or rear end portions of a strip 17. The 70 strip 17 extends beyond the forward end of the tongue 15 and is provided with an opening in which will be secured a shackle 18 carried by a chain 19, this chain 19 carries at its free end a hook 20 for engaging the 75 forward end portion of the car.

Pairs of the skids will be jointly used in practice, one being positioned under a wheel of and on each side of the car. When the car reaches an incline and it is desired to prevent the car from travelling too rapidly down an incline the skid will be put in place with one skid on each side of the car. The skid will rest upon the rail as shown and the hook will engage the forward end portion of the car. The car will then be permitted to move down the incline and as soon as the front wheels engage the skid they will move on to the skid as shown in Figure 1 so that they will not engage the track and therefore the car will drag along the track and be prevented from moving too rapidly. When the bottom of the incline is reached and the car has moved on to the level stretch, the car may be moved backward and the wheels will roll off of the skid thus releasing the skids and permitting them to be removed from the track. It will thus be seen that the skids can be very easily put in place and the cars will roll on to the skids of their own momentum and that they may be easily removed by simply moving the cars rearwardly so that the wheels will move off of the skids. If by any means the skid should be broken it can be easily removed by simply removing the bolts 16 and a new skid put in place. It will thus be seen that there

100 has been provided a skid which will be very 105

efficient in operation and very strong and durable and which can be very easily put in place and removed.

Having thus described the invention, what

5 I claim is:

A skid for insertion intermediate a car wheel and track having its upper surface substantially parallel with the tread of the track, a tongue integral with the skid and 10 extending upwardly and above said surface at the forward end of the skid, an attaching strip member on said skid in contact with the upper surface of said tongue and

extending rearwardly to said surface, and the rear end of the strip terminating in advance of the rear end of the skid and constituting an abutment rising from said surface and in the path of travel of the car wheel.

In testimony whereof I affix my signature in presence of two witnesses.

THOMAS L. CAMPBELL.

Witnesses:

WILLIAM CAMPBELL,
JAMES CAMPBELL.
